Primary Examiner — Katrina A Betton*(74) Attorney, Agent, or Firm* — Whitaker Chalk Swindle & Schwartz PLLC; Charles Gunter(57) **CLAIM**

The ornamental design for a goose neck trailer hitch, as shown and described.

DESCRIPTION

FIG. 1 is a front perspective view of the goose neck trailer hitch of the invention;

FIG. 2 is a front elevation view of the goose neck trailer hitch of FIG. 1;

FIG. 3 is a rear elevation view of the goose neck trailer hitch of FIG. 1;

FIG. 4 is a right side view of the goose neck trailer hitch of FIG. 1;

FIG. 5 is a left side view of the goose neck trailer hitch of FIG. 1;

FIG. 6 is a top plan view of the goose neck trailer hitch of FIG. 1;

FIG. 7 is a bottom plan view of the goose neck trailer hitch of FIG. 1; and,

FIG. 8 is an environmental view of the goose neck trailer hitch of the invention showing its intended use mounted in the bed of a truck.

The broken lines in the drawings depict portions of the design and environmental features that form no part of the claimed design.

1 Claim, 6 Drawing Sheets(56)
